UNITED STATES PATENT OFFICE.

DANIEL O. WARD, OF OAK PARK, ILLINOIS, ASSIGNOR TO GRIP NUT COMPANY, OF CHICAGO, ILLINOIS, A CORPORATION OF ILLINOIS.

SELF-LOCKING NUT.

No. 800,189.

Specification of Letters Patent.

Patented Sept. 26, 1905.

Application filed August 25, 1904. Serial No. 222,189.

To all whom it may concern:

Be it known that I, DANIEL O. WARD, a citizen of the United States of America, residing at Oak Park, in the county of Cook and State 5 of Illinois, have invented certain new and useful Improvements in Self-Locking Nuts, of which the following is a description.

My invention belongs to that class of devices intended to lock a nut in position on its 10 bolt in such a manner that it may not be accidentally disarranged therefrom.

The object of my improvement is to produce a simple, economical, and thoroughly effective device for such purpose.

15 To this end my invention consists in the novel construction and arrangement shown and described and more particularly pointed out in the claims.

In the accompanying drawings, wherein like 20 reference characters indicate like or corresponding parts, Figure 1 is a plan view of my improved nut. Fig. 2 is a perspective view of a slight modification of the same. Fig. 3 is an edge view of my improved nut. Fig. 25 4 is a sectional view of a modification. Fig. 5 is a sectional view showing one manner of using my improved nut, and Fig. 6 is a sectional view on line 6-6 of Fig. 5.

As shown in the drawings, 1 is a spring- 30 metal nut-blank slightly bent or curved in cross-section into a concavo-convex form and provided with a centrally-disposed substantially square aperture 2. The aperture is screw-threaded by means of an ordinary tap, 35 resulting in a screw-threaded section 3 on each side of the aperture and at the corners a plane section not so threaded. This results in two locking-corners 4 on each side, or eight locking-corners in all, which in operation 40 tend to engage with the bolt to prevent accidental retraction of the nut.

When the nut is screwed down and is in operative position, any tendency to back off is resisted by the locking-corners, which are naturally 45 brought into lateral impinging contact with the bolt-threads. The constant spring keeps a tension on the parts. In a square aperture the sides strengthen one another against spreading and improper engagement 50 with the bolt. In an oblong hole it is found in practice that a limit is reached when further strain upon the nut tends to simply spread the sides apart, resulting in improper or imperfect engagement and weakness. My

invention overcomes this objectionable weakness in a simple and effective manner, as the metal of the whole nut is uniformly disposed, and hence the strength is uniform throughout, obviating weak points. 55

In the form shown in Fig. 4 two opposite 60 sides of the plate, as at 5, are formed at right angles to the plate, providing extensions for convenience in positioning a wrench when assembling the parts. These wrench extensions may be formed on all sides, if preferred; but in practice it is found that when formed as shown in Fig. 4 they satisfy every 65 demand.

Figs. 5 and 6 show my improved nut in use 70 in an ordinary construction, in which 6 is the bolt, 7, 8 are the parts secured together, and 9 is the usual nut. My improved nut is shown at 1, illustrating the operation in a simple structure.

I am aware of the patent issued to J. Pearson 75 on February 2, 1897, No. 576,148, and do not claim the construction there described.

Having thus described my invention, what I claim as new, and desire to secure by Letters 80 Patent, is—

1. As an article of manufacture, a self-locking nut comprising a plate of spring metal concave in cross-section and provided with a substantially square aperture therethrough having the four sides partially screw-threaded 85 to present eight locking-corners.

2. As an article of manufacture, a self-locking nut comprising a cylindrically concavo-convex plate of spring metal, provided with a substantially square aperture therethrough 90 having a part of each of its sides screw-threaded, whereby when the nut is flattened the threads of the threaded sections are thrown into different planes.

3. A self-locking nut, consisting of a nut 95 formed of spring material and having a cylindrically concave working face, the usual screw-threaded opening being substantially square with its screw-threads formed near the center of each of its sides, whereby when the nut is flattened the threads of the threaded sections are thrown into different planes. 100

4. A self-locking nut, comprising a cylindrically concavo-convex plate of spring metal, provided with a substantially square aperture 105 therethrough, with part of each of its sides screw-threaded, and provided with wrench extensions upon the straight edges of the nut.

5. A self-locking nut, consisting of a nut having a cylindrically concave working face, the screw-threads formed in its threaded opening being interrupted by four spaces extending through said nut, substantially evenly spaced about the threaded wall, whereby when the nut is flattened the threads of the threaded sections are thrown into different planes.
6. A self-locking nut, consisting of a nut having a cylindrically concave working face the screw-threads formed in its threaded opening being interrupted by four grooves extending through said nut, substantially evenly spaced about its threaded wall, whereby when the nut is flattened the threads of the threaded sections are thrown into different planes.
7. A self-locking nut, consisting of a cylindrically concavo-convex plate, having a screw-threaded central opening in which the threads are interrupted by four spaces extending

through said nut, substantially evenly spaced about said threaded opening, whereby when the nut is flattened the threads of the threaded sections are thrown into different planes.

8. A self-locking nut, consisting of a cylindrically concavo-convex plate, having a screw-threaded central opening in which the threads are interrupted along four lines extending through said nut, substantially evenly spaced about said threaded opening, and provided with wrench extensions upon the straight edges of the nut.

In testimony whereof I have hereunto signed my name in the presence of two subscribing witnesses.

DANIEL O. WARD.
